ROTARY SPIT UNIT FOR ROASTING

James A. Goodsell, Hudson, Mich.

Application July 6, 1953, Serial No. 25,809

Term of patent 14 years

(Cl. D81—10)

To all whom it may concern:

Be it known that I, James A. Goodsell, a citizen of the United States, residing at Hudson, Michigan, have invented a new, original, and ornamental Design for a Rotary Spit Unit for Roasting, of which the following is a specification, reference being made to the accompanying drawing, forming a part thereof, wherein:

Fig. 1 is a plan view of a rotary spit unit for roasting embodying my new design;

Fig. 2 is an enlarged fragmentary side view thereof;

Fig. 3 is a similar bottom view thereof;

Fig. 4 is an end view; and

Fig. 5 is a view taken on line 5—5 of Fig. 2.

I claim:

The ornamental design for a rotary spit unit for roasting, as shown.

JAMES A. GOODSELL.
